Primary Examiner — Samantha Wood*Assistant Examiner* — Vanessa Martinez(57) **CLAIM**

The ornamental design for a magnetic light bulb, as shown and described.

DESCRIPTION

1. Magnetic light bulb

1.1 : Perspective

1.2 : Perspective

1.3 : Front

1.4 : Back

1.5 : Left

1.6 : Right

1.7 : Top

1.8 : Bottom

1.9 : Enlarged

The parts shown by means of broken lines in the reproductions are not part of the claimed design; 1.9 is an enlarged view of the portion taken at line 9 in 1.2; the dash-dot-dash lines in 1.2, 1.9, and the label "9" in 1.2 are for the purpose of depicting the cut line of the enlarged view and form no part of the claimed design.

1 Claim, 9 Drawing Sheets(56)
